8 Claims. (Cl. 332—13)

1

The present invention relates to systems for distributing, among a plurality of independent output channels, successive electrical impulses supplied through a common input channel, these systems being of the kind described in my co-pending U. S. applications, Ser. No. 739,018, filed April 2, 1947, for Improvements in Signal Distributing Systems and Ser. No. 739,019, filed April 2, 1947, for Electrical Transmission Systems and based upon the use of combined capacitors supplied with polyphase current or currents.

An object of my invention is to obtain high voltage electrical impulses in each of the independent channels. For this purpose, according to my invention, I make use of a gas discharge tube (for instance a tube containing helium or mercury vapor at low pressure), in particular of the cooled type with a big condensation chamber, and the conductivity of the tube is controlled so as to last, on each successive impulse, for a time which is a function of the amplitude of the impulse to be transmitted or stored up. I vary the time at which the arc is struck in accordance with the intensity of the current to be transmitted. This tube conductivity control may be performed by means of a tube different from that which serves to ensure the storing up of the impulse, but according to a preferred embodiment I make use of the multiple anode gas discharge tube which distributes the impulses to the different channels for simultaneously ensuring amplification. I employ for this purpose the known "phase control" method for gas discharge tubes (a method which is now very much employed in mercury vapor rectifiers, thyratrons). Control of the grid potential, which ensures the starting of the current flow at the desired time in the gas discharge tube, may be ensured by means of suitable auxiliary vacuum tubes. For instance, I make use of a saw-tooth anode voltage, or of a tube having several control grids, one of the grids receiving the modulation, and the second a saw-tooth voltage.

But, according to a preferred embodiment of my invention, I make use of a multiple anode tube including at least two successive control grids: the first of the grids receives the modulation, whereas the second receives a saw-tooth voltage. At the same time each of the multiple anodes successively receives, as described in the above stated patent applications, a complex voltage which passes through a positive value (peak of the curve) for an extremely short time interval in the course of every period. This positive value is supplied successively to each of the anodes, which thus receive the amplified impulses.

2

The saw-tooth voltage is preferably obtained from oscillators synchronized to the scanning frequency, by means of a complex voltage generator as described in the above mentioned prior U. S. applications.

According to a preferred modification of my invention, the second grid is mounted like the "anode" of a relaxation oscillation generator, which permits of avoiding the use of a synchronized auxiliary voltage.

Preferred embodiments of my invention will be hereinafter described with reference to the accompanying drawings, given merely by way of indication and in which:

Fig. 1 is a diagrammatical view of a tube arrangement according to my invention;

Fig. 2 is a curve showing the form of saw-tooth oscillation preferably used according to my invention;

Fig. 3 is a diagrammatical view of an arrangement for compensating for parasitic capacities;

Fig. 4 shows a modification of the arrangement of Fig. 1 embodying the use of a two grid tube.

For certain applications, and in particular in the case of a "high speed" signal distributor intended to supply the vertical conductors of a television receiving screen, as described in particular in my French Patent No. 860,481 of June 28, 1939, entitled "Improvements in big screen television receivers," it is necessary to obtain in each of the independent channels a relatively high voltage (at least about one hundred volts). As the capacity of said vertical conductors is rather high (for instance 250 electrostatic units), in view of

the high rate of the impulses (if the frame includes for instance 600 horizontal lines scanned twenty-five times per second the rate of the impulses is 15,000 per second) it is necessary to obtain a relatively high power in each of the channels (for instance 0.5 watt). The multiple anode distributing tube which feeds several of these channels simultaneously (for instance 80 in the case of an arrangement including 800 points per line and 10 distributing tubes having each 80 anodes) must therefore be able to supply a very substantial power (theoretically 40 watts, but actually much more as a consequence of the bad transformation output). Furthermore, the supply tube must have a very low internal resistance, as

the instantaneous current in the tube is to reach very high values (eighty times 1.5 milliamperes, i. e. 120 milliamperes approximately). Accordingly, when high vacuum tubes are employed, it is necessary to make use of very big ones. Fig.

55 1 clearly shows the advantage resulting from the

use of gas discharge tubes of the kind including a control grid. In these tubes, and according to a known method, it is possible to obtain a progressive modulation by controlling, for each alternation and as a function of the impulse amplitude, the time at which the arc is struck. The supply voltage may be an alternating one but it may also have any complex shape provided that it passes through zero. Fig. 1 shows the application of this principle to my invention. I have shown at 61 the cathode, at 62 the control grid, at 63, 63', 63'' some of the multiple anodes. According to the method above referred to, each of the anodes is given a complex voltage (diagrammatically represented by 64, 64', 64'') having at a given time a very sharp positive maximum, these times occurring successively for the respective anodes. These voltages are obtained through the use of energizing distribution devices 65, 66, 67, 68 and 65', 66', 67' and 68' as already described in my above mentioned U. S. applications. But, according to the present invention, the distribution device which supplies the successive impulses (coming from the common input channel) is no longer caused to act upon the cathode 61 of the multiple anode rectifier tube but upon the grid of a control tube 72. I arrange so that each of the anodes becomes positive during the hatched period 64, 64', 64'', etc. On the other hand the striking of the arc is delayed (according to the now conventional method of phase "grid" control) more or less (at 69, 69', 69'') under control of the modulation so that the mean value (hatched portion) of the current individually supplied to each of the anodes becomes a function of the impulse amplitude.

In order to obtain this result, I make use, on Fig. 1, of an amplifier tube 72 on the plate of which a saw-tooth voltage is impressed by a generator 70. I have shown at 71 the variations of this voltage as a function of time. The grid 76 of tube 72 receives the input signal modulation from 78. This modulation is represented as a function of time, by a succession of horizontal lines 77, 77', 77'', having different respective ordinates corresponding to the amplitudes of the impulses that arrive successively through the input channel. The modulation from 78 acts upon the tube grid, while saw-tooth generator 70 acts upon the plate. The plate current is shown by curve 75, 75', 75'' and the voltage drop across resistance 73 controls the grid potential of tube 62 in such manner as to cause the arc to be struck at the desired time. The hatched portions 69, 69', 69'' thus have respective areas which correspond to the amplitudes of the successive impulses.

The current thus supplied through each anode has for its effect to store up, owing to resistors 78, 79', 79'', in each of the line condensers (80, 80', 80'') a charge which depends upon the impulse amplitude. Suitable means (not shown) are then provided to discharge these condensers.

In order to produce saw-tooth voltage 70, I may, according to my invention (Fig. 2) have recourse to a complex voltage generator based upon the principle of the static voltage distribution described in my above mentioned prior U. S. applications. I superimpose on the fundamental sinusoid 83 its first harmonic (or several harmonics if necessary) with a suitable choice of amplitude and phase, so as to obtain a resultant curve 74 which differs but little from the desired saw-tooth shape (dot and dash lines).

According to another feature of my invention,

the voltage induced by the tube capacity in the anodes which receive the impulses is constantly balanced by a voltage of opposite sign equal (or proportional) at any time to the instantaneous value of the impulse. Fig. 3 shows a device for generating this compensating voltage. On this figure, 85 represents the coil through which are supplied the high frequency waves which carry the modulation. I make use of two oscillating circuits coupled with this coil and tuned to the carrier frequency: 86 and 89. The first of these circuits supplies a rectifier 88 which feeds impulses of a given sign to a resistor 81. These impulses are fed to the cathode 92 of the multiple anode distributor tube. The second oscillator circuit 86 has its output connected to a second rectifier 87 which supplies oscillation of opposite sign to a resistor 88. The voltage thus obtained is to exert upon anodes 94, 94', etc., an influence capable of compensating that exerted by cathode 92. For this purpose, I make use of a capacitor 95, 95' of a capacity equal to that of the parasitic capacitor 92—94 (if voltage 88 is equal to that of 91). If, on the contrary, the voltage of 88 is different from 91, I make use of inversely proportional capacities.

As in the preceding arrangements, I produce in anode 94, 94', etc., a complex voltage by means of capacitors 98, 98', etc. The utilization circuit 30 is connected through a rejector coil 99. A capacitor 97 and a reactance coil 97' compensate the induction produced in the utilization circuit by capacitor 98. The voltages necessary for obtaining these inductions are obtained from oscillators 96 synchronized with the line impulses 83. Discharge is obtained, according to a feature of my invention, by means of a valve 100 the anode of which, connected with a capacitor 102, receives a variable voltage of substantially rectangular form. This voltage is obtained through a system for the distribution of polyphase voltages of different frequencies supplied by an oscillator synchronized with impulses 93 and of a bias battery 106. The stored up voltage corresponding to the 45 impulse acts upon the grid of an amplifier tube 107 placed in the independent output line.

According to a preferred embodiment of my invention, the striking of the arc at the desired time can be controlled without having recourse to an auxiliary control tube (tube 72 of Fig. 1), by making use of a gas discharge tube having several control grids. Fig. 4 illustrates this embodiment. The second grid 111 is connected with a relaxation oscillation generator, including a capacity 112 and a high resistance 113. The voltage impressed on the successive anodes 114, 115, 116 is represented, as a function of time, by curves 117, 118, 119. Modulation 108 is applied between cathode 110 and the first grid 109. On the drawing I have shown two different amplitudes 124 and 127 of the modulation (corresponding to two successive impulses, for instance).

Discharge of condenser 112 into anode grid 111 causes the striking of the arc at the proper time, because the working of anode grid 111 depends upon the potential of grid 109. Explanation of the operation appears clearly by referring to Fig. 4: It has been supposed that at 123 the tube ceases to be ionized (to act as a conductor) due to the fact that the anode voltage 117 becomes zero. In these conditions, the potential of the condenser assumes a given value 120, always the same. From this time on, as the tube acts as an insulating element, the voltage across the terminals of condenser 112 gradually increases as

illustrated by inclined line 121. If grid 109 is then given a voltage such as 124, the arc is struck between cathode 110 and anode grid 111 at point 125, which makes it possible for anode 115 to discharge (hatched portion 126). The tube keeps acting as a conductor as long as the anode is discharging, that is to say as far as point 128. From this time on, the tube acts as an insulating element. Condenser 112 is again charged as represented by inclined straight line 129. If, at this time, control grid 109 has another value, such as 127, more negative than its preceding value, anode grid 111 is energized at a later time, at 130, thus starting a current 131 (hatched portion) in anode 116 less important than the current which has been started in anode 115 and so on. It is thus possible to replace by a single tube having several grids a relatively complicated arrangement which would necessitate several tubes and means for producing a saw-tooth voltage.

The features above set forth can be employed in combination for ensuring high speed static distribution of the impulses in a multi-elementary television receiver screen or in a multi-plex telephony system.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. In a system of the kind described, the combination of a single input channel carrying successive electrical impulses of different amplitudes and equal durations, a plurality of independent output channels, a gaseous discharge device having a cathode, at least one control electrode and a plurality of anodes, means connecting each of said anodes to a different one of said output channels, means for impressing on said anodes one at a time and in succession periodic voltage variations having sharp maxima, said voltage variations extending positively with respect to said cathode and means comprising said control electrode for varying the time of current flow from each of said anodes to said cathode in response to said periodic voltage variations in accordance with the amplitudes of said impulses.

2. A system for distributing successive impulses from a single input channel to a plurality of independent output channels which comprises, in combination, a gas discharge tube including a cathode, at least one control grid and a plurality of anodes connected with said independent output channels respectively, means for impressing on said anodes, at the frequency of the incoming impulses, periodical voltage variations with sharp maxima occurring successively in a predetermined order for the respective anodes, to bring said anodes successively into cooperating voltage relation with said cathode, and means, including at least said control grid and a generator of saw-tooth voltage variations connected with said grid, for varying the time at which the arc is struck in said tube in the course of each voltage variation period in accordance with the amplitude of the incoming impulse corresponding to this period.

3. A system for distributing successive impulses

from a single input channel to a plurality of independent output channels which comprises, in combination, a gas discharge tube including a cathode, a control grid and a plurality of anodes connected with said independent output channels respectively, means for impressing on said anodes, at the frequency of the incoming impulses, periodical voltage variations with sharp maxima occurring successively in a predetermined order for the respective anodes, to bring said anodes successively into cooperating voltage relation with said cathode, an auxiliary control tube including a plate, a grid and a filament, means for impressing on said plate a saw-tooth voltage of the same period as the above mentioned voltage variations, means for impressing on said last mentioned grid the voltage impulses from said input channel, and means for coupling the plate circuit of said auxiliary control tube with the grid circuit of said gas discharge tube, whereby the arc is struck in said last mentioned tube at a time in each period which varies in accordance with the amplitude of the impulse corresponding to this period.

4. In a system of the kind described, the combination of a single input channel carrying successive electrical impulses of different amplitudes and equal durations, a plurality of independent output channels, means for distributing successive ones of said impulses from said single input channel to successive ones of said output channels comprising a gaseous discharge tube having a cathode, a plurality of anodes and at least two control electrodes interposed in current flow controlling relation between said cathode and said anodes, means for impressing periodic positive voltage pulses on said anodes in succession and in synchronism with said electrical impulses, means for impressing on one of said grids a recurrent periodic saw-tooth voltage synchronized with said impulses, and means for impressing said electrical impulses on the other of said grids.

5. A system according to claim 2 in which said generator of saw tooth voltage variations is of the kind adapted to combine a fundamental sinusoidal oscillation with at least one harmonic thereof.

6. A system for distributing successive impulses from a single input channel to a plurality of independent output channels which comprises, in combination, a tube including a cathode and a plurality of anodes connected with said independent output channels respectively, means for impressing on said anodes, at the frequency of the incoming impulses, periodical voltage variations with sharp maxima occurring successively in a predetermined order for the respective anodes, to bring said anodes successively into cooperating voltage relation with said cathode, means for impressing the incoming voltage variations on said cathode, and means for imparting to each of said independent channels a voltage opposed in direction and proportional in magnitude to the instantaneous value of the corresponding impulse voltage, to compensate that induced in said independent channel by the capacity of said tube.

7. A system for distributing successive impulses from a single input channel to a plurality of independent output channels which comprises, in combination, a tube including a cathode and a plurality of anodes connected with said independent output channels respectively, means for impressing on said anodes, at the frequency of

the incoming impulses, periodical voltage variations with sharp maximums occurring successively in a predetermined order for the respective anodes, to bring said anodes successively into cooperating voltage relation with said cathode, means for rectifying the incoming voltage impulse variations and impressing the rectified voltage on said cathode, a plurality of condensers each connected on one side to one of said independent channels, means for rectifying said incoming voltage impulse variations in opposition with said first mentioned rectifying means and impressing the rectified voltage thus obtained to the other sides of said condensers, to compensate the voltage induced in said independent channel by the capacity of said tube.

8. In a system of the kind described, the combination of a single input channel for supplying successive electrical impulses of successively different amplitude and equal duration, a plurality of independent output channels for successive ones of said electrical impulses, a gaseous discharge device having a cathode, at least one control electrode, and a plurality of anodes, means connecting each of said plurality of anodes to a different one of said output channels, means for impressing on each of said anodes, one at a

time and in succession, a similar positive voltage pulse, and means comprising said at least one control electrode for controlling the duration of current flow from each of said anodes to said cathode in accordance with the amplitude of that one of said electrical impulses which occurs while that anode is subjected to one of said positive voltage pulses.
